MARTIN HEMLEB, OF ELIZABETH, NEW JERSEY, ASSIGNOR, BY MESNE ASSIGNMENTS, TO THE SINGER MANUFACTURING COMPANY, OF ELIZABETHPORT, NEW JERSEY, A CORPORATION OF NEW JERSEY.

MOTOR SUPPORT.

Application filed May 24, 1920. Serial No. 383,708.

To all whom it may concern:

Be it known that I, MARTIN HEMLEB, a citizen of the United States, residing at Elizabeth, in the county of Union and State 5 of New Jersey, have invented new and useful Improvements in Motor Supports, of which the following is a specification.

This invention relates to motor supports.

It is particularly applicable for rigidly 10 supporting a belt drive motor on a sewing machine standard but is not limited thereto.

It is particularly desirable in providing a support for a belt driven motor to employ a bracket having a means for adjustably supporting the motor thereon to permit the same to be applied as a compact unit to various types of machines in which the motor is mounted at different distances from the standard. The different distances may 15 be necessitated by the character of the machine cover, the configuration of the standard, or to the style of machine, as for example the drop head type, to which the unit is applied. The present invention aims 20 to provide a suitable mounting to meet the above conditions, without requiring substantial change between driving centers, so a belt of uniform length may be employed.

One of the objects of this invention is to 25 provide a rigid support for a motor which may be applied to the standard of different types of machines.

Another object is to provide a rigid support for a belt driven motor, which may be 30 applied as a compact unit to different types of machines to permit a belt of uniform length to be employed.

Another object is to provide a rigid support for a motor having means to permit 35 the distance between the motor and standard to be varied and still use one belt.

Another object is to provide a rigid support and means to permit a motor to be adjusted thereon in a path approximating the 40 arc of a circle, without appreciably altering the distance between driving centers.

Another object is to provide a bracket for 45 a belt driven motor having means associated therewith to permit the motor to be adjusted on the bracket when first applied to a machine without substantially varying the distance between driving centers when a material change is made in the distance

between the sewing machine and the motor.

Another object is to provide a bracket 55 having a means for rigidly and adjustably supporting a belt driven motor, so that the bracket, motor and a belt of uniform length may be applied as a standard unit to different types of machines necessitating a 60 change in distance between the standard and motor.

Other objects and advantages will herein-after appear.

One embodiment of the invention is illus- 65 trated in the accompanying drawing.

In the drawings:

Fig. 1 is an end elevation, with the fly-wheel broken away, showing a sewing machine standard with the motor supported 70 thereon.

Fig. 2 is a bottom plan of the motor and bracket.

Fig. 3 is a broken section on line 3—3 of Fig. 1 showing the means for mounting the 75 motor on the bracket.

Fig. 4 is a perspective of the bracket.

A sewing machine standard 1 is provided with the usual driven member or pulley 2 and the fly-wheel 3. A knurled lock unit 80 4 is arranged in the usual manner to disengage the fly-wheel and pulley from the sewing machine mechanism when desired.

A bracket 5 is provided having at one end a vertical arm 6 with a groove 7 therein, 85 which groove is seated on a raised bearing 8 extending vertically on the standard 1. The bracket is rigidly held in position on the standard by a threaded stud 9 passing through an aperture 10 in the vertical arm, 90 and into a threaded aperture in the standard 1. Only one stud is required as the cooperating groove 7 and raised bearing 8 prevents turning of the bracket 5 about its point of support. Any other suitable means 95 may be provided for rigidly mounting the bracket on the standard.

The bracket 5 is provided with an inclined arm 11 at one end, on which a motor 12 is rigidly mounted. A means is provided 100 for adjusting the motor longitudinally of the arm. The arm 11 is provided with a groove 13 which is seated on a raised bearing 14 of the motor. A plurality of spaced apertures 15 extend through the arm 11 and 105 a plurality of threaded apertures 16 are

formed in the raised bearing 14 of the motor but are differently spaced than apertures 15 in the arm 11. The guideway 13 stands substantially at right angles to line 5 *a—b* through the center of the pulley 2. To fix the motor in one position, one of each of the apertures 15, 16 are brought in alinement and a stud 17 or the like is passed therethrough, and threaded in the 10 motor 12. The broken section of Figure 3 shows more clearly the means of securing the motor 12 on the inclined arm 11.

An idler pulley 18 is mounted at the end of an arm 19 pivotally carried upon the 15 motor 12. The idler 18 is yieldingly pressed by a spring 20 on a belt 21 guided over a driving pulley 22 of the motor and the driven pulley 2. One end of the spring 20 is fixed. The spring is shown coiled about 20 a stud 23, on which the arm 19 is mounted, and the other end of the spring is bent about the arm 19 so that the action of the spring will be exerted thereon. It is to be understood that any other suitable means 25 may be employed for yieldingly pressing the idler 18 on the belt 21.

One position of the motor 12 on the arm 11 is shown in full lines in Figure 1. This represents the position of the motor, bracket 30 and belt when applied as a unit, to a certain type of sewing machine. In this position there is a certain distance between the centers of the driving pulley 22 and the driven member 2.

35 In applying the motor, bracket and belt as a standard unit to another type of sewing machine, conditions may be such as to require a different distance between the axis of the pulley 22 and the vertical axis of 40 the standard 1. That is, if the standard 1 of another type of machine is thicker than that shown, it will be necessary to space the motor at a greater distance from the vertical axis of such thicker standard in order 45 to clear the wall thereof.

In such case the motor 12 may be moved to another position on the arm 11 as indicated by the dotted outline in Figure 1. This adjustment in position may be effected 50 by moving the motor 12 upon the arm 11 until two of the apertures are in alinement, when the threaded stud may be again inserted. By having the two apertures on the motor 12 and inclined arm 11 suitably 55 spaced it may be possible to obtain any desired adjustment of the motor. Any other means may be employed for adjusting the motor position.

60 In each of the different positions the distance between the motor and standard may be substantially or appreciably changed, without substantially altering the distance between the driving centers. One belt or a belt of uniform length may thus be employed for either position of the motor on

the bracket. The end of the bracket supporting the motor may be formed as the arc of a circle.

The feature permitting the adjustment of the motor is of importance, because it enables the bracket, motor and belt of uniform length to be applied as a standard unit to various machines in which the distance between the motor and standard may vary considerable. 75

The invention contained herein is, of course, susceptible of other embodiments and adaptations.

What is claimed is:

1. A motor attachment for belt driven 80 sewing machines comprising a bracket adapted for attachment to the frame standard of a sewing machine, and a motor rigidly mounted on said bracket and having a power-shaft and belt-pulley, there being provision for adjustment of the motor on the bracket in an inclined direction substantially normal to the center line connecting the axes of the motor and machine shafts, whereby a given motor attachment 90 may be applied to sewing machines of various types while maintaining a uniform length of belt-drive. 95

2. The combination of a standard, a driven member rotatably mounted thereon, a bracket rigidly mounted on the standard, a motor having a driving pulley, adjustably mounted on the bracket, flexible driving means between the driving and driven members, and an idler yieldingly riding on the 100 flexible driving means. 105

3. A motor supporting bracket adapted to be fastened rigidly to a sewing machine standard, comprising a vertical arm having a groove therein for engaging a tongue on the standard, an inclined arm having a groove therein for engaging a tongue on the motor, and a horizontal body member connecting the vertical and inclined arms, each arm having an aperture therein for receiving a clamping member for rigidly fastening the respective arms to the standard and motor. 110

4. The combination of a motor supporting bracket adapted to be mounted rigidly on a sewing machine standard in which a driven member is rotatably mounted, said bracket having an inclined arm, and a motor adjustably mounted on the inclined arm, the inclined arm being so constructed and having such an inclination as to maintain a driving connection between the motor and the driven member for the different motor positions. 115

5. The combination of a sewing machine 125 standard, a driven member rotatably mounted thereon a bracket rigidly mounted on the standard, said bracket having an inclined arm at one end, a motor having a driving pulley, rigidly mounted on the inclined 130

- arm, a driving belt connecting the driving pulley and driven member, an idler yieldingly mounted, for the belt, and means for adjusting the motor longitudinally of the 5 inclined bracket arm to vary the distance between the centers of the driving pulley and driven member so that a belt of constant length may be employed when the motor is in any one of the adjusted positions on the 10 arm.
6. The combination of a bracket having an inclined arm, a motor having a driving pulley rigidly mounted on the arm, a belt for the pulley, an idler for the belt, and 15 means for mounting the motor at a plurality of points on the arm, the said bracket being adapted to be rigidly mounted on any one of a number of standards having a driven member rotatably mounted thereon, 20 whereby a driving connection may be established between the driving pulley and the driven member without altering the belt length.
7. The combination of a bracket adapted 25 to be supported on a sewing machine standard upon which a driven pulley is mounted, the said bracket having an inclined arm, a motor mounted on the inclined arm, a driving pulley for the motor a belt adapted to 30 connect the driving and driven pulley, an idler arm pivotally supported on the motor, an idler pulley rotatably supported on the idler arm and adapted to ride upon the belt, yielding means cooperating with the idler 35 arm adapted to press the idler pulley on the belt, and means for adjusting the motor on the inclined arm whereby the bracket, motor and belt may be applied as a unit to various types of sewing machine standards to effect 40 a driving relation with a belt of one length under the various conditions involving a change in distance between driving centers.
8. In combination with a sewing machine 45 standard having a driven member rotatably mounted thereon, a motor supporting bracket having a vertical arm at one end to be fastened rigidly to the standard and an inclined arm at the other end, a motor rigidly fastened to the inclined arm, and means
- for adjusting the motor longitudinally 50 along the arm, the inclination of the arm being such that the motor is maintained in driving relation to the driven member for the different motor positions.
9. The combination of a sewing machine 55 standard having a driven member rotatably mounted thereon, a bracket having at one end a vertical arm and at the other an inclined arm, means for rigidly fastening the vertical arm to the standard, a motor rigidly mounted on the inclined arm, and means associated with the motor and the inclined arm whereby the motor may be mounted thereon in any one of a plurality of positions so as to maintain a driving connection 60 between the motor and driven member for the different motor positions.
10. A support for mounting on a sewing machine standard a motor having a belt driving connection to a driven member supported by the standard, comprising a bracket having means at one end thereof for rigidly fastening the same to the standard, an inclined arm at the other end of the bracket, and means for rigidly mounting 70 the motor on the inclined arm in any one of a plurality of positions, the inclination of the arm being such that a belt of uniform length may be employed to connect the motor and the driven member for the different 75 motor positions.
11. The combination of a motor supporting bracket having at one end means for rigidly fastening the same to a sewing machine standard so the bracket will project 80 horizontally therefrom, an inclined arm at the other end of the bracket, a motor, a tongue and groove connection between the motor and the inclined arm whereby the motor may be adjusted on the inclined arm 85 to vary the horizontal and vertical position of the motor with respect to the standard, and means for rigidly fastening the motor to the inclined arm in any one of a plurality of adjusted positions.
- In witness whereof, I have hereunto subscribed my name. 90

MARTIN HEMLEB.
